UNITED STATES PATENT OFFICE.

ALEXANDER M. GOW, OF DULUTH, MINNESOTA, AND FRANK E. KEESE, OF ISHPEMING,
MICHIGAN.

LOADER.

1,223,578.

Specification of Letters Patent. Patented Apr. 24, 1917.

Application filed March 13, 1916. Serial No. 83,963.

To all whom it may concern:

Be it known that we, ALEXANDER M. Gow and FRANK E. KEESE, citizens of the United States, and residents of Duluth, in the county of St. Louis and State of Minnesota, and Ishpeming, in the county of Marquette and State of Michigan, respectively, have invented certain new and useful Improvements in Loaders, of which the following is a specification.

Our invention comprises a mechanism for loading material into cars, and is designed especially for use underground in mines. After the ore, either in the breast of a drift, or in a "slice," is broken down by blasting, it is customary to shovel it into small tram cars. As the drift proceeds the tracks are laid so that the distance between the car and the broken ore shall be as little as possible. The ore is loaded by shovels and this loading, or "mucking," as it is called, is extremely laborious inasmuch as the "mucker" has his back to the car and faces the broken ore, and must throw ore over his shoulder into the car. A great many machines have been proposed to do this work, but as yet practically all "mucking" is done by hand. It is obvious that it is essential that a loading machine shall be free from complicated mechanism. The conditions under which the machine must work are extremely severe, and the making of repairs underground is a very difficult matter. In the design of our machine we have tried not so much to reduce the number of men employed as to lessen the amount of their labor, or with a given amount of manual labor, to increase the tonnage of ore handled.

The invention will be more readily understood by reference to the accompanying drawings, wherein—

Figure 1 is a longitudinal section of a mining drift showing an application of our loader;

Fig. 2 is a cross section through the drift on the line 2—2 of Fig. 1, and

Fig. 3 is a view similar to Fig. 1 showing a slightly modified construction as applied to a rock drift.

Referring more particularly to Figs. 1 and 2, it will be seen that we provide an overhead carrier consisting of two channels 10 placed back-to-back and united by means of a cover plate 11 at their top edges. Se-

cured to and extending transversely of the carrier are I-beams 12, to the ends of which are hinged the legs 13—13, 14—14, each of which is provided with an extension nut 15 for adjusting the length of the leg. The exact form of the supports or braces is not important and other types of braces may be utilized to advantage. The upper edge of the carrying member rests against the cross timbers 16, the tracks or carrying element 10 being preferably inclined rearwardly, as shown. On the outer end of the track member 10, we provide a platform or bracket 17, on which is mounted a motor 18, provided with a suitable drum. A rope, or cable, extends from the drum between the two channels 10, passing around a sheave 19, thence rearwardly over a sheave 20 carried by the trolley best shown in Fig. 3, then downward into engagement with a scoop 21. The cable is directly connected to the scoop through a bail 22. The trolley consists of a frame 23, which carries trolley wheels 24, adapted to run upon the lower flanges of the channels 10. The shaft 25, upon which the sheave 20 is mounted, also acts to support a hook 26, which may be actuated by means of a handle or lever 27, best shown in Fig. 1. The hook 26 acts to engage the bail 22 of the scoop and support the scoop in its travel to and from the rear end of the track. A plurality of apertures 28 in the track are intended to accommodate a pin 28^a which act as stops to limit the forward travel of the trolley.

In operation, it being assumed that the material 29 is to be loaded into the cars 30, the parts are located as shown in Fig. 1. The scoop 21 is then filled with the material by a combined manual and power operation through the agency of the motor and cable, whereupon the scoop is lifted to the dotted-line position and into engagement with the hook 26, whereupon the trolley is caused to travel down the inclined track, preferably by gravity, and the scoop is dumped into the car. The trolley and scoop may then be returned to the initial position through the agency of the motor and the scoop disengaged from the hook by actuating the handle or lever 27, whereupon the operations are repeated. After the material within the range of the scoop has been loaded, the parts are dismantled and set up in a new location. It will be seen that the

range of the loading apparatus is practically limited only by the length of the cable, as the scoop, after having been loaded, may be dragged along the ground by the motor until it is elevated into engagement with the trolley; therefore, that the parts constituting the track and support may serve their purpose for a considerable length of time in one location.

10 A device such as described provides a unitary loading structure; that is, one which may be handled as a unit in advancing it in the drift. It is so arranged that the beam which acts as the rigid track has a long 15 overhung advance end adapted to be projected into the extreme inner end of the drift; that the cable which acts on the scoop passes over a sheave on the extreme inner or overhanging end of the beam and consequently 20 the pulling action on the scoop is toward the pile. This is the natural method of shoveling.

The supporting legs for the beam are in the form of diverging braces, the adjusting 25 feature thereof providing for forcing the beam against the roof of the tunnel. When in contact with the roof the inclined legs assure stability of the structure against forces in all directions.

30 A particular advantage arises from our method of mounting the motor in the drift. It will be understood that the space within the drift is limited and also that the tram car to be loaded must be brought to a point beneath the beam which acts as a track; furthermore that the motor must be rigidly secured. It cannot be mounted on or secured to the tram car track as the tram car must occupy the extreme inner end of the track. 35 40 We overcome all these difficulties by rigidly securing the motor to the beam; it is thus out of the way—is moved with the beam and it requires no separate fastening devices to make it rigid.

45 It is obvious also that the construction shown is typical only, and that modifications may be made therein without departure from the spirit of our invention, as set forth in the appended claims.

50 We claim:

1. In a mine loading device, the combination of a beam providing a runway, means for rigidly and readily removably mounting said beam relative to the walls of the space containing it, a car track on the floor of the space beneath said beam, a motor mounted above said track to permit free passage of a car on the track therebeneath, and car

loading means operable by said motor and movable on said runway, substantially as described. 60

2. In a mine loader, the combination of a beam adapted to be rigidly located with its inner end in the extreme inner end of the drift, a tram car track beneath the outer 65 end of said beam, a motor mounted above said track, a scoop, and cable connections between said motor and scoop, the parts being so arranged that ore located beneath the inner end of said beam is transported by the 70 scoop to a point above a car on the track beneath the outer end of the beam and there dumped, substantially as described.

3. In an underground loading machine, a rearwardly inclined, vertically adjustable, 75 trolley carrying, hollow track; transverse members secured to the track, hinged adjustable legs secured to the members, a sheave wheel secured to the front end of the track, a trolley adapted to travel on the track, a 80 sheave carried by the trolley, a drum secured to the rear end of the track, means for driving the drum, a rope adapted to be wound on the drum, passing longitudinally through the hollow track and over each 85 sheave, a scoop secured to the free end of the rope, and means on the trolley for securing the scoop in raised position.

4. In a device of the class described, the combination of a track member and adjustable legs attached to said track member, said track comprising two angular members in spaced relation, a sheave mounted on one end of said track, a drum mounted at the opposite end of said track, a trolley adapted 90 to travel on said track, a sheave mounted on said trolley, a rope wound on said drum and extending between the track members and over the sheaves, a scoop to which the other end of said rope is attached, means on 95 said trolley for supporting said scoop when in raised position and means connected to said drum for the operation thereon, substantially as described.

Signed at Duluth, Minn., this 23d day of 105 February, A. D. 1916.
